(57) **CLAIM**

The ornamental design for a surgeon control apparatus as shown and described.

DESCRIPTION

FIG. 1 is a perspective view of a surgeon control apparatus according to an embodiment;

FIG. 2 is a front elevational view of the surgeon control apparatus of FIG. 1;

FIG. 3 is a rear elevational view of the surgeon control apparatus of FIG. 1;

FIG. 4 is a left elevational view of the surgeon control apparatus of FIG. 1;

FIG. 5 is a right elevational view of the surgeon control apparatus of FIG. 1;

FIG. 6 is a top plan view of the surgeon control apparatus of FIG. 1; and,

FIG. 7 is a bottom plan view of the surgeon control apparatus of FIG. 1.

The broken lines in FIGS. 1-7 show portions of the surgeon control apparatus that form no part of the claimed design.
